SHAKER CONVEYER

Clarence H. Brown, Chicago, Ill., assignor to
 Goodman Manufacturing Company, Chicago,
 Ill., a corporation of Illinois

Application August 21, 1941, Serial No. 407,799

6 Claims. (Cl. 198—220)

This invention relates to improvements in shaker conveyers and more particularly relates to a new and improved swivel for permitting one trough section of a shaker conveyer trough line to deliver material to another trough section of the conveyer trough line, when positioned laterally with respect to said other trough section.

The principal objects of my invention are to provide a new and improved form of swivel for a shaker conveyer trough line including a novel means for controlling the path of swinging movement of the laterally swingable trough section of the conveyer.

A more specific object of my invention is to provide a novel form of articulated connection between two trough sections of a conveyer including a pair of crossing links pivotally connected at one of their ends to a fixed base and having pivotal connection at their opposite ends with a sliding support means for the laterally swingable trough section of the conveyer, for controlling the path of swinging movement of said support means.

Other objects of my invention will appear from time to time as the following specification proceeds and with reference to the accompanying drawings wherein:

Figure 1 is a plan view of a swivel constructed in accordance with my invention, with certain parts broken away and certain other parts shown in section in order to more clearly illustrate certain details of my invention;

Figure 2 is an enlarged longitudinal sectional view taken substantially along line 2—2 of Figure 1;

Figure 3 is a partial fragmentary transverse sectional view taken substantially along line 3—3 of Figure 1;

Figure 4 is a partial fragmentary transverse sectional view taken substantially along line 4—4 of Figure 1;

Figure 5 is an enlarged detail view showing certain details of the anti-friction mounting for the reciprocating trough section;

Figure 6 is an enlarged detail sectional view taken substantially along line 6—6 of Figure 1; and

Figure 7 is an enlarged detail sectional view taken substantially along line 7—7 of Figure 1.

In the drawings the embodiment of my invention illustrated is shown as providing an articulated connection between a driving trough section 10 and a driven trough section 11 of a shaker conveyer trough line, to permit material to be carried from the driven to the driving

trough section when the driven trough section is positioned laterally with respect to the driving trough section, so the conveyer may carry material around corners or so a pick-up member on the forward end of the driven trough section may pick up material from the extreme corners of a wide room or may be extended along a cross cut or entry at an angle to the main part of the conveyer, to pick up material therefrom.

10 The articulated connection between the driving and driven trough sections of the conveyer includes a base 12 adapted to be firmly held in position on the ground during reciprocation of the conveyer by means of a plurality of jacks 13, 13 engageable at their lower ends with sockets 14, 14 in said base and with the mine roof at their upper ends.

A connecting trough section 15, having a widened outwardly flared receiving end, with curved 20 sides, is reciprocably mounted on said base on a plurality of aligned laterally spaced grooved rollers 17, 17 rotatable about parallel vertical axis. Each of said rollers, as herein shown, is journaled on a vertical shaft 18. Said shafts are 25 mounted on the base 12, as their lower ends, and extend through a support member 19 mounted on and extending longitudinally along said base and over the top of said rollers. As herein shown, four rollers are provided on each side of said connecting trough section, although any desired number of rollers may be provided, and each group of spaced rollers is adapted to have supporting engagement with a longitudinally extending rod 20, engaging the grooved portion thereof. 30 Said rods are mounted on and extend along the lower portion of a frame 21, which forms a support for said connecting trough section.

The forward end of the trough section 10 is 35 adapted to be connected with the forward end of the connecting trough section by means of the usual connecting bolts 22, 23 extending through abutting eyes 24, 24.

A forward connecting trough section 25, similar to the trough section 15, is mounted on the 40 base in forwardly spaced relation with respect to said trough section on a reciprocably movable support frame 26. Said frame has a pair of laterally spaced longitudinally extending rods 27, 27, which engage the grooves or 45 grooved rollers 28, 28, mounted on a transversely slidable plate 29. Said rollers are mounted between the top of said plate and the underside of the upper portion of laterally spaced longitudinally extending support members 30, 30, on vertical shafts 31, 31. Said slidable plate is movable 50

transversely of said base, so the entire support for said forward trough section may be laterally moved across said base. Said forward connecting trough section is connected with the driven trough section 11 by means of the usual connecting bolts 33, 33 extending through laterally spaced eyes 34, 34.

An intermediate trough section 35 having outwardly curved sides, at its ends, which conform to the form of the forward and rear connecting trough sections 15 and 25, is provided to bridge the gap between the connecting trough sections 25 and 15. Said intermediate trough section is pivotally connected at its ends, to adjacent ends of said connecting trough sections and has the discharge end of the connecting trough section 25 nested in the forward end thereof and is nested within the receiving end of the connecting trough section 15. Said intermediate trough section bridges the gap between said connecting trough sections and also splits the angle between said trough sections, to eliminate abrupt turns from one trough section to the other and to prevent the piling up of material at the turn.

The intermediate trough section 35 has a stub shaft 36 secured to and depending from its bottom and journaled in the frame 21 on a bearing 37, mounted in a bearing sleeve 38 mounted on said frame. Said sleeve extends through a bored portion of said frame and upwardly therefrom through the connecting trough section 15, and forms a mounting for said connecting trough section on said frame.

The opposite end of the intermediate trough section 35 underlaps the forward connecting trough section 25 and is mounted on a bearing sleeve 40, secured to the frame 26 and projecting upwardly therefrom. Said forward connecting trough section has a stub shaft 43 secured thereto and depending therefrom, which extends through a bearing 44, mounted in said bearing sleeve. The driven trough section 11 and forward connecting trough section 25 may thus be transversely moved across the base 12 about the vertical axes of the stub shafts 38 and 43.

Referring now in particular to the novel means for controlling transverse movement of the plate 29 and the roller support for the forward connecting trough section 25 across the base plate 12, to cause the plate 29 and rollers 28, 29 to move in the same path as the path of movement of the connecting trough section 25, a pair of crossing control links 46 and 47 are provided. The furcations of the rear bifurcated end of the link 46 extend on opposite sides of a bracket member 49, mounted on the base 12. Said link is pivotally connected to said bracket member by means of a pivotal pin 50 and extends from said bracket member diagonally across said base, and its forward end is pivotally connected to a bracket member 51, projecting rearwardly from the plate 29, by a pivotal pin 52.

The link 47 is like the link 46, but its bifurcated end portions are so arranged that said link will cross under the link 46, as is shown in Figures 1 and 6. Said link is pivotally connected to a bracket 53, at its rear end, by means of a pivotal pin 54, and is connected to a bracket 55 at its forward end by means of a pivotal pin 56. As herein shown, the pivotal pins 50 and 54 are positioned equal distances from opposite sides of the stub shaft 36 and are spaced forwardly therefrom a slight distance and the pivotal pins 52 and 56 are mounted on the plate 29 beyond the rear end thereof and are laterally spaced the 75

same distance apart as the pins 50 and 54 and equal distances from the center of the shaft 43. Said links, crossing each other, thus form a controlling connection between the base and the plate 29, for controlling the path of movement of said plate so it will move about the spaced vertical axes of connection of the intermediate trough section 35 to the connecting trough sections 15 and 25.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In an articulated trough connection for a shaker conveyer trough line, a base, a trough section guided on said base for reciprocable movement with respect thereto, another trough section guided on said base for reciprocable movement with respect thereto, an intermediate connecting trough section pivotally connecting adjacent ends of said trough sections together so material will flow from one of said trough sections to the other and so one of said trough sections may be swung laterally with respect to the other, and means for causing said laterally swingable trough section to move about a pair of parallel spaced axes including a pair of crossing links pivotally connected to said base at one of their ends and having controlling connection at their opposite ends with the means for guiding said laterally swingable trough section on said base.

2. In an articulated connection for a shaker conveyer trough line, a base, a driving trough section, a driven trough section, means for supporting a receiving end of said driving trough section for reciprocable movement with respect to said base, means for supporting a discharge end of said driven trough section for reciprocable movement with respect to said base, said last mentioned means being laterally movable with respect to said base, to permit lateral swinging movement of said driven trough section with respect to said base, and means connected between said laterally movable support means and said base, for causing said support means to move across said base about a pair of parallel spaced axes including a pair of crossing links having pivotal connection with said base at one of their ends, for movement about a pair of parallel spaced vertical axes, and having controlling connection with said laterally movable support member at their opposite ends.

3. In an articulated connection for a shaker conveyer trough line, a base, a driving trough section, a driven trough section, means for supporting a receiving end of said driving trough section for reciprocable movement with respect to said base, means for supporting a discharge end of said driven trough section for reciprocable movement with respect to said base, said last mentioned means being laterally movable with respect to said base, to permit lateral swinging movement of said driven trough section with respect to said base, and means connected between said laterally movable support means and said base for causing said support means to move across said base about a pair of parallel spaced axes including a pair of crossing links

having pivotal connection with said base at one of their ends, for pivotal movement about a pair of parallel spaced vertical axes, and having pivotal connection with said laterally movable support member at their opposite ends.

4. In an articulated connection for a shaker conveyer trough line, a base, a driving trough section, a driven trough section, means for supporting a receiving end of said driving trough section, for reciprocable movement with respect to said base, means for supporting a discharge end of said driven trough section for reciprocable movement with respect to said base, said last mentioned means being laterally movable with respect to said base, to permit lateral swinging movement of said driven trough section with respect to said base, and means connected between said laterally movable support means and said base, for causing said support means to move across said base about a pair of parallel spaced axes including a pair of crossing links having pivotal connection with said base at one of their ends, for movement about a pair of laterally spaced vertical axes disposed within the limits of said connecting trough section and having pivotal connection with said laterally movable support member at their opposite ends for movement about a pair of laterally spaced vertical axes disposed within the limits of said intermediate trough section.

5. In an articulated connection for a shaker conveyer trough line, a base, a driving trough section, a driven trough section, means for supporting a receiving end of said driving trough section for reciprocable movement with respect to said base, means for supporting a discharge end of said driven trough section for reciprocable movement with respect to said base, said last mentioned means being laterally movable

with respect to said base, to permit lateral swinging movement of said driven trough section with respect to said base, and means connected between said laterally movable support means and said base, for causing said support means to move across said base about a pair of parallel spaced axes including a pair of crossing links having pivotal connection with said base at one of their ends for pivotal movement about a pair of laterally spaced vertical axes disposed within the limits of said connecting trough section and in advance of and on equal sides of the axis of connection of said intermediate trough section to said driving trough section, and having pivotal connection with said laterally movable support member at their opposite ends, for movement about a pair of laterally spaced vertical axes disposed to the rear of and on equal sides of the axis of connection of said intermediate trough section to said driving trough section.

6. In an articulated connection for a shaker conveyer trough line, a base, a driving trough section, a driven trough section, means for supporting a receiving end of said driving trough section for reciprocable movement with respect to said base, anti-friction means for supporting a discharge end of said driven trough section for reciprocable movement with respect to said base, said last mentioned anti-friction means being laterally movable with respect to said base, and a pair of cross links connected between said laterally movable anti-friction support means and said base for causing said support means to move in a controlled path about the axes of connection of said driving and driven trough sections to said intermediate connecting trough section.

CLARENCE H. BROWN.
